UNITED STATES PATENT OFFICE.

JOSEPH A. GROEBLI, OF NEW YORK, N. Y., ASSIGNOR TO KURSHEEDT MANUFACTURING COMPANY, OF NEW YORK, N. Y., A CORPORATION OF NEW YORK.

TUBULAR BRAID.

SPECIFICATION forming part of Letters Patent No. 698,490, dated April 29, 1902.

Application filed November 29, 1901. Serial No. 84,059. (No model.)

To all whom it may concern:

Be it known that I, JOSEPH A. GROEBLI, a citizen of the United States, and a resident of the borough of Manhattan, city, county, and State of New York, have invented certain new and useful Improvements in Tubular Braids, of which the following is a specification.

My invention relates to tubular braids, and has for its object to produce a tubular structure having lines or wales of a general undulating form extending longitudinally thereof and selvage edges of a general undulating contour united by a thread-braid or filament preferably laid in the nature of a loop-stitch.

15 In the accompanying drawings I have illustrated a tubular braid in which my invention is embodied.

In the drawings, Figure I illustrates one example of the braid in which my invention is embodied. Fig. II represents the braid as it would appear if the loop-stitch were cut out and the braid were spread open.

It will be understood that the braid illustrated in the drawings and hereinafter described is but one of the many forms in which my invention may be embodied.

In the drawings, *a* indicates the braid, whose ribs or wales extend longitudinally thereof in a general undulating form, two free edges *b c* or selvages being formed as undulating edges, which are united in the present instance by a thread *d* entering each selvage. This thread *d* is bound in with each selvage and constitutes a bond or binder between the 35 two selvages. If this thread or binder be cut out and the braid spread out, it will assume the form shown in Fig. II, which figure clearly shows the undulating courses of the wales or ribs indicated by the crossing of the 40 constituent threads.

The braid may be constructed in any suitable manner. One mode of constructing the said braid is to form it upon a flat-braiding machine having two selvage-bars and interposed between the two selvage-bars a race-way open at the side, into which opening the

braider-threads are adapted to pass as they are thrown upon the selvage-bars as the carriers reach the turning-point of their travel. As the selvage-threads come into the race-way the shuttle carrying the thread *d* travels around its circuit, thereby binding the shuttle-thread around the braider-threads.

It will be understood that a binder the equivalent of a thread may be employed to effect the binding of the two selvages and that the thread or binder is distinct both as to the manner in which it is bound into the braid and in function from the individual braider-threads.

Having described my invention, what I claim, and desire to secure by Letters Patent, is—

1. As a new and useful article of manufacture a tubular braid consisting of a braided body, having wales or ribs of a general undulating form running longitudinally thereof and selvage edges united by a thread or filament after the manner of a loop-stitch.

2. As a new and useful article of manufacture, a tubular braid having selvage edges of a general undulating form bound together by a thread substantially as set forth and ribs or wales of a general undulating form running longitudinally thereof.

3. As a new and useful article of manufacture, a tubular braid consisting of a braided body, having two selvage edges of wavy form, the waves of one edge fitting the waves of the other edge, and means for uniting said edges substantially as described.

4. As a new and useful article of manufacture, a tubular braid having extending longitudinally thereof wavy edges, the waves of one edge fitting the depressions between the waves of the other edge, and a binder-thread entering both edges and binding the said edges together.

JOSEPH A. GROEBLI.
